COMBINATION LOCK

Mathieu de Wrangell, Paris, France, assignor to
 Déwé, Clichy (Seine), France, a French company with limited responsibility

Application August 2, 1938, Serial No. 222,681
 In France August 2, 1937

Section 3, Public Law 690, August 8, 1946
 Patent expires August 2, 1957

3 Claims. (Cl. 70—310)

1

The object of the present invention is an improvement to locks of the double operation type, i. e. of the type capable of operating either as a combination lock or as a free lock, the improvement referring especially to the type of lock comprising a movable locking member, the displacement of which is dependent upon a combination device and which operates with a bolt movable with respect to said locking member.

The improvement according to the invention permits the realisation of a double operating lock of the type set forth, which is of a simple and robust construction and easy in operation.

The lock according to the present invention is characterized by the fact that the locking member of the lock comprises, at the end next to the bolt, a movable stop member adapted to block the bolt in the closing position when the lock operates as a combination lock, and capable of being moved clear from the path of the bolt after backward movement of said locking member into the blocking discs in the position of the selected combination, for permitting the free movement of the bolt in spite of a later disengagement of said locking member from said blocking discs and the mixing up of the combination.

The effect of this arrangement is to simplify the construction of the lock while permitting the spring provided for pushing the locking member into the blocking position of the bolt to remain in a nearly expanded position during the operation as a free lock. On the other hand, this arrangement will permit an elastic mounting of the swinging or pivoting stop member, movable with respect to its actuating knob, thereby permitting, as will be seen below, to pass instantaneously and without operating the combination, which may be mixed up, from the operation as a combination lock to that of a free lock.

On the drawing an embodiment of the invention has been represented by way of example.

Figures 1, 2 and 3 are diagrammatic plan views, in three different positions to be described below, of a double operating lock particularly adapted for drawers, suit cases, doors and the like, while

Figure 4 is a sectional elevation along the plane IV—IV, partly broken away, of the right hand side of Figure 1.

The lock shown comprises a locking member 114 free to move with respect to the base plate 169 of the lock and the stepped part 113 of which

is adapted to cooperate in a known manner with the notches 113' of the flanged locking discs 155, 156, 157 also arranged in the form of steps and actuated from the outside by the combination discs 155', 156', 157' (Figure 4) respectively. The front part of the locking member 114 carries a rotating stop piece 145 adapted to cooperate with the bolt 142 of the lock and actuated by the pin 144. The rotation of this stop piece 145 is guided by a lug 147 of the locking element 114 against which may abut either the nose 146 or the nose 148 of piece 145, while the bolt 142 is provided on its side with an edge of a notch 149 which, when the bolt is moved downward, will strike against the nose 146 of piece 145 when the latter lies in the locking position shown in Figure 1. The piece 145 carries a slot 145' engaged by a flattened part of the pin 144 provided with a small handle 144'; a spring 145'' resting on the right part of piece 145 pushes the latter towards the left against the bolt 142.

In the position of Figure 1, the locking nose 146, engaged under the notch 149 of bolt 142, maintains the latter closed; the steps 113 abut against the locking discs 155, 156, 157 and prevent any backward movement of the locking element 114 towards the right and subsequent freeing of the nose 146.

If, in forming the combination, the slots 113' formed in the edges of the three discs 155, 156, 157 are brought in alignment before the steps 113 and the lever 144' is pushed towards the right, the locking element 114 and the piece 145 will both be moved to the right; until the nose 146 has cleared the notch 149 of the bolt, the lever 144' will be displaced parallel to itself, it will then swing to the right and the nose 146 will then occupy the inclined position shown in Figure 2.

If the lever 144' be then permitted to return towards the left while maintained inclined towards the right, the nose 146 will abut against the side of the bolt 142, the lever 144' being in the middle of slot 145', and the locking element 114 will resume its initial position under the effect of the spring 124 (Figure 3), the steps 113 being again clear of the discs 155, 156, 157, while the combination of the latter may again be mixed up.

As long as the nose 146 is in the position of Figure 3, the bolt 142 may be actuated freely by means of its button 151 and the lock will operate as if it were not a combination lock.

When it is desired to lock again the bolt, it is only necessary to rotate the lever 144' to the left; this being possible due to the presence of the slot 145' permitting the pivoting member 145 to move elastically towards the right, the nose 146 will thus engage again the notch 149 into which it is pushed by its spring 145'', resuming the position of Figure 1; the lock can then only be opened by the person knowing and forming the unlocking combination.

What I claim is:

1. A combination lock comprising a number of combination discs, a number of locking discs connected with said combination discs respectively, a locking member cooperating with said locking discs and free to move towards the latter when they are in the desired combination position, a bolt separate from said locking member, a movable stop piece cooperating with said bolt to maintain it in its closing position, means for bringing said movable stop piece in a position rendering the opening and closing movements of said bolt free, and operative only after moving said locking member towards said locking discs in the combination position, and means for maintaining the first said means in said position corresponding to the free movement of said bolt in order to allow the free movement of said bolt to subsist in spite of the back movement of said locking member to its initial locking position and of the mixing up of the combination discs.

2. In a combination lock according to claim 1, elastic means cooperating with said movable stop piece and permitting the latter to be brought back, without necessity of forming the combination, from its position corresponding to the free movement of said bolt into its initial position in which said free movement of said bolt is suppressed.

3. A combination lock according to claim 1, 10 in which the first said means comprise a handle adapted to produce simultaneously, when actuated, on one hand the movement of said locking member towards said locking discs placed in the combination position and, on the other hand, 15 the movement of said movable stop piece into the position corresponding to the free movement of said bolt.
